(57) **CLAIM**

The ornamental design for a remote control unit for controlling a valve actuator, as shown and described.

DESCRIPTION

FIG. 1 is top plan view of a remote control unit for controlling a valve actuator in accordance with my invention;

FIG. 2 is a left side elevation view thereof, the right side being a mirror image thereof;

FIG. 3 is a bottom end view;

FIG. 4 is a perspective view from the bottom thereof;

FIG. 5 is a perspective view from the top thereof;

FIG. 6 is a top end view thereof; and,

FIG. 7 is a bottom end view thereof.
